UNITED STATES PATENT OFFICE.

MICHAEL J. LAWLOR, OF POUGHKEEPSIE, NEW YORK.

DUMB-WAITER.

SPECIFICATION forming part of Letters Patent No. 360,027, dated March 29, 1887.

Application filed August 4, 1886. Serial No. 210,014. (No model.)

To all whom it may concern:

Be it known that I, MICHAEL J. LAWLOR, a citizen of the United States, residing at Poughkeepsie, in the county of Dutchess and State of New York, have invented a new and useful Improvement in Dumb-Waiters, Lifts, and like Elevating Mechanism, of which the following is a specification.

The object of my invention is to make a dumb-waiter with its parts so arranged as to reduce friction of working parts, sharp bends in the rope holding the car and weight, and having guide-wheels so arranged that the balance-weight may be conducted to any desired position around the car; and it consists in the combination, construction, and arrangement of its parts, as hereinafter more fully described. I attain these objects by the mechanism illustrated in the accompanying drawings, in which—

Figure 1 is a front view of my improved dumb-waiter or lift as shown when the balance-weight is carried to the right-hand side of the car and in the plane of the weight F and wheel B. Fig. 2 is a plan view of Fig. 1. Fig. 3 is a front view of my invention, taken at line x x, Fig. 4, showing the balance-weight conveyed in a different direction from that shown in Fig. 1. Fig. 4 is a plan view of Fig. 3.

Similar letters refer to similar parts throughout the several views.

A shows the hoist-wheel attached to the shaft b, over which an endless rope passes in a V-shaped groove, by which power is transmitted to the load.

B is a pulley attached to the shaft b, over which the rope holding the car and weight passes.

C is a guide-wheel, which guides the counter-balancing-rope from the car to the pulley B, and in some cases it may be omitted and a slot in the shelf substituted.

D and E are guide-wheels, which, when arranged in the plane of each other and so placed that wheel D is directly under the pulley B, and it takes the rope H from said wheel B in a line perpendicular to the shelf on which the wheels D and E rest, guide the rope H to any desired position at the angles α and β , as shown in Fig. 4.

F is the balance-weight, which should balance the car or be one or two pounds heavier.

G is the car into which the articles to be raised or lowered are placed.

H is the rope which connects the car with the balance-weight.

I is an endless hoisting-rope, by which power is transmitted to the load.

J shows the feet or standards which support the frame L L.

K shows a part of the frame L L, and made so that it rigidly connects the parts L L, so as to make a solid and stationary bearing for the shaft b to revolve in, thus reducing the friction which is the result in separate frames or standards.

I will describe my invention. On the rotary shaft b, which carries the hoist-wheel A, I place a pulley, B, securely fastened to said shaft and occupying any position on the same as may be necessary or convenience of construction may require. I arrange the wheels C, D, and E as shown, so that the counterbalance-rope H may be carried up and over wheel C from the center of the car G, guided by the said wheel C to the pulley B, over which the said rope H passes down and over the guide-wheel D, then along and over the guide-wheel E to the balance-weight F. When the weight is to be placed on the right-hand side of the car and in the plane of the pulley B, as in Figs. 1 and 2, I place the wheels D and E as far apart as may be convenient, so as to save the rope from wear by avoiding sharp bends and kinks.

The guide-wheels D and E are also so placed that the rope passing over them just passes the rope as it comes up from the car without touching. When the weight is to be placed in any other position than in the plane of the wheel B, as in the positions shown in Figs. 3 and 4, I place the guide-wheel D so that the rope H will come down from the pulley B perpendicular to the shelf on which the frame is supported, and make a perpendicular line in the plane of the pulley B, and around this line as an axis I revolve the guide-wheel D in the direction required—that is, in any direction in the angles α and β on that side of the line parallel to the shaft b through the axis α , and when the weight is to be on the other side of

this line I change the arrangement of the wheels, as in Figs. 1 and 2, but moving the guide-wheel D inward, so as to be in the plane of the perpendicular from the pulley B, as hereinbefore described. The guide-wheel C may in some cases be left out, and a long slot cut in the shelf instead of said wheel.

Having thus described my invention, what I claim, and desire to secure by Letters Patent,
10 is—

The combination of a dumb-waiter car having connected thereto a counterbalance-weight by means of the rope H, the hoisting wheel or drum, having on its axle the counterpoise sup-

porting-wheel B, the guide-wheel C, the 15 guide-wheel D, arranged at an angle to the supporting-wheel B, and the guide-wheel E, in the same plane as the wheel D, the counterpoise rope H being passed from the car over the supporting-wheel B, thence under the 20 guide-wheel D, and across at an angle to the axle of the hoisting-wheel to the guide-wheel E, all substantially as described.

MICHAEL J. LAWLOR.
